UNITED STATES PATENT OFFICE

151,715

DESIGN FOR A RECORDING STUDIO BUILDING OR THE LIKE

Michael Rettinger, Encino, Calif., assignor to
Radio Corporation of America, a corporation of
Delaware

Application September 17, 1946, Serial No. 133,363

Term of patent 14 years

(Cl. D13—1)

To all whom it may concern:

Be it known that I, Michael Rettinger, a citizen of the United States and a resident of Encino, in the county of Los Angeles and the State of California, have invented a new, original, and ornamental Design for a Recording Studio Building or the like, of which the following is a specification, reference being had to the accompanying drawing, forming a part thereof.

Figure 1 is an elevational view of the interior of the front half of a recording studio building, showing my new design;

Figure 2 is an elevational view of the interior

of the rear half of a recording studio building, showing my new design; and

Fig. 3 is a perspective view of the exterior of a recording studio building, showing my new design, the view being taken from and looking beyond the front wall toward the rear of the building.

I claim:

The ornamental design for a recording studio building or the like, substantially as shown.

MICHAEL RETTINGER.
